UNITED STATES PATENT OFFICE.

ANDREW J. SEYLER, OF CEDARVILLE, ILLINOIS.

MIDDLES-PURIFIER.

SPECIFICATION forming part of Letters Patent No. 255,036, dated March 14, 1882.

Application filed December 13, 1881. (No model.)

To all whom it may concern:

Be it known that I, ANDREW J. SEYLER, of Cedarville, in the county of Stephenson and State of Illinois, have invented certain new and useful Improvements in Middlings-Purifiers; and I do hereby declare that the following is a full, clear, and exact description thereof, reference being had to the accompanying drawings, and to the letters of reference 5 marked thereon, which form part of this specification, in which—

Figure 1 is a side elevation; Fig. 2, a central longitudinal section; Fig. 3, an end elevation; Fig. 4, a view of the cut-off apron, and Fig. 5 15 a detail perspective view of the sieves and their frames.

My invention relates to certain novel improvements in middlings-purifiers, which will be fully understood from the following description when taken in connection with the annexed drawings:

The letter A designates the frame of the machine, which is suitably housed in by means of stationary and removable boards, herein- 25 after specially referred to.

C designates a fan-case mounted above the inclined sieves D and E at one end of the frame A, and containing a rotary fan, which receives its motion from a main driving-shaft, 30 F, journaled in brackets on the said frame. The fan-case is provided with end openings, to which valves are applied for regulating the force of the currents through the machine. It is also provided with a discharge-spout, C', 35 through which the light foreign matters separated from the middlings are discharged.

G designates a hopper, into which the middlings are fed; and G' is an upright chest having a semi-cylindrical top, which is divided into 40 an ascending passage, a, and a descending passage, a', by means of an inclined partition, a². At the discharge end of the hopper G is an air-inlet, b, and an inclined chute, b', near which latter the partition a² terminates. The 45 discharge end of the descending passage a' of the chest G terminates above the sieve D in front of an inclined board, H, which is rigid with the side housing of frame A, and which is arranged in a chamber, H', communicating 50 directly with the fan-case C.

Below the front ends of the sieves D E are

adjustable valves c c, for regulating the induction currents of air, as indicated by the course of the arrows. Below the lower sieve, E, is a shoe, I, having inclined bottoms terminating in a discharge-spout, I', for the purified middlings; and at the rear extremity of this shoe is a spout, I², for the discharge of the "seconds" or impure middlings. The top and bottom sieves have cloths of different grades or degrees of fineness 55 stretched on their frames f g, so arranged that the finest cloth is nearest the front or highest ends of the screens and the coarsest cloth is nearest the rear ends of the same. Each one of the sieve-frames is fitted into grooves made 60 in the inner sides of vibrating frames J, which are suspended by hangers h from the fixed boards of the housing of frame A.

The front transverse pieces, i, of the frames J are slotted partly through at the middle of 70 their length to receive screws j, which are fixed into the front cross-pieces of the sieve-frame. By means of thumb-nuts on said screws the sieve-frames can be screwed to the frames J, so that they will be rocked together. By 75 this construction I am able to make the middlings on the screens travel fast or slow, according to the quality of the middlings acted on. To make the middlings travel fast over the sieves, one or both, I loosen the thumb 80 nut or nuts and push the frame J more or less toward the rear or tail end of the machine. This throws the middlings up from and back on the cloth. The front ends of the central strips, p, of the screens are pressed against by 85 springs j' j', and the rear projecting ends of the said central strips are acted on by a vertical knocker, k, which is rigidly secured on one end of an arm, k', to the opposite end of which is pivoted lever K, fulcrumed to the 90 frame A at y. (See Fig. 1.)

The upper or shorter arm of lever K is provided with an anti-friction wheel, m, which is acted upon by a prismatic tappet-wheel, L, keyed on the main driving-shaft F. By these 95 means the sieves and the frames J receive rapid vibration longitudinally and give a slight tossing motion to the middlings while passing downward over thin cloths of different degrees of fineness.

The shoe I, which is provided with the inclined bottoms for the "firsts" or purified mid-

dlings, is attached to the fixed side boards of the housing by means of hangers h' , and this shoe is connected by a rod, l , to the lower arm of lever K , so as to receive vibration therefrom. A spring, s , fixed to a cross-piece of frame A , acts constantly against pin s' on said shoe to give the forward strokes to it.

Between the two sieves D and E , and secured rigidly to the side housing of the frame A , are a series of chute-boards, N , which incline backward in planes parallel to each other, and are arranged equidistant from each other, with their lower edges in close relation to the bottom sieve.

15 Beneath the rear part of the bottom sieve, E , I arrange a flexible imperforate apron, O , one end of which is secured to a horizontal roller, m' , and the other end is attached to a transverse slat, n , one end of which is exposed to view on the outside of the housing. This slat n is attached by narrow flexible strips $O' O'$ to another roller, m^2 . The two rollers have ratchet-wheels r on their outer exposed ends, with which pawls r' engage for preventing the 25 rollers from turning. The apron O is equal in width to the width of the sieve E , and of a length sufficient when unwound from roller m' to reach as far as the roller m^2 and form a cut-off for the material which falls from about 30 two-thirds of the rear portion of the screen E . This apron and its rollers vibrate with the lower frame, J , and when the apron is fully wound on roller m' all of the material passing through the lower screen will fall upon the inclined bottom of the shoe I and pass off through the discharge-spout I' . By unwinding the said cut-off apron O more or less all the middlings sifting through the bottom sieve, E , from the indicator n' to the tail of this screen will fall 35 on the apron and be discharged from it into the spout I^2 as second middlings. By these means a very nice separation of the different grades of middlings is obtained. The bran is discharged from the tail ends of the screens D and E into a spout, Q .

45 I will now briefly describe the operation.

The middlings are fed into the hopper G , from which they pass into the upward air-passage, a . As they leave hopper G they are 50 caught by a current of air, entering passages a and b under the hopper and passing up and over an adjustable valve, a^3 , thence down through passage a' , and upward over the board H to the fan-case C . The middlings, as they 55 pass into the lower end of the passage a , have applied to them a very strong blast, and if any are carried over the valve a^3 into passage a' they will be thrown down on the sieve D in front of board H , and nothing but the light 60 useless matters will be carried over this board to and discharged from the fan-case. The mid-

dlings which are too heavy to be carried by the air-currents fall down the chute b' and are delivered on the front part of the top sieve, D . As the middlings which sift through this top 65 sieve fall upon the inclined chutes N they are directed by the latter backward or toward the head of the second sieve, E , the same distance they traveled toward the tail end of the top sieve.

70 By having the sieve-frames clothed with fine cloth at the end where the middlings are first fed into them and graded from these points to the tails coarse enough to let all of the middlings through, and combining with these sieves the chutes N , it will be seen that the middlings in passing through a given section of the top sieve are partly relieved of their impurities, and, falling on chutes N , are carried toward the head of the second or lower sieve and go 80 through the same process on finer cloth.

What I claim as new, and desire to secure by Letters Patent, is—

1. The combination of the feed-hopper G , the upright passages $a a'$, and valve a^3 therein, 85 the air-inlet passage b , the chute b' , the board H , the shaking-sieve D , and a suction-fan, substantially as described.

2. The combination of the shaking-sieve frame, a cross-strip fixed to its head, the shaking-frame J , a slotted cross-strip fixed to its head, the bolt j , the binding-nut for securing the two frames together, and means for shaking the latter, substantially as described. 90

3. The combination of the stationary inclined chutes N , the shaking-sieves arranged above and below said chutes, the valves $c c$, at or below the heads of the sieves, an adjustable grading device, o , below the sieve E , and a suction-fan, C , substantially as described. 95

4. The combination of the shaking-sieves, the hangers thereof, the knocker k , its arm k' , lever K , anti-friction wheel m , and tappet-wheel L , substantially as described. 100

5. The combination of a flexible rolling cut-off apron adjustable at one end, as described, with the shaking-screen E , the lower end of said apron terminating near the lower end of said screen, the laterally-discharging spout I^2 , and the shaking-shoe I , all substantially as 105 for the purpose set forth.

6. The combination of the cut-off apron O , its rollers $m' m^2$, strips $O' O'$, ratchet-wheel r , pawls r' , strip n , pointer n' , and a shaking-screen, substantially as described. 110

115 In testimony that I claim the foregoing as my own I affix my signature in presence of two witnesses.

ANDREW J. SEYLER.
